DESIGN FOR A TEXTILE FABRIC OR SIMILAR ARTICLE

Ferdinand W. Ellington, Jamaica, N. Y., assignor
to Delman, Inc., New York, N. Y., a corpora-
tion of New York

Application January 15, 1934, Serial No. 50,399

Term of patent 3½ years

To all whom it may concern:

Be it known that I, FERDINAND W. ELLINGTON, a citizen of the United States, residing in Jamaica, Long Island, in the county of Queens and State of New York, have invented a new, original, and ornamental Design for Textile Fabric or Similar Article, of which the following is a specification, reference being had to the accompanying drawing, forming part thereof.

The figure is a plan view of a textile fabric showing my new design.

In the embodiment of the present design shown in the drawing, the fabric has a nacreous ap-

pearance provided by coloring in green, red and yellow illustrated by the curved lines which represent the color green, the straight lines which represent the color red, and the dots which represent the color yellow, the green and red coloring predominating.

The drawing shows the entire design of the present invention for a piece of fabric of definite length and width.

I claim:

The ornamental design for a textile fabric or similar article as shown and described.

FERDINAND W. ELLINGTON.
